UNITED STATES PATENT OFFICE

2,533,121

VALVE SPRING COMPRESSOR

Harry W. Kulp, Lancaster, Pa., assignor to K-D
Manufacturing Company, a corporation of
Pennsylvania

Application May 8, 1947, Serial No. 746,768

4 Claims. (Cl. 29—218)

1

This invention relates to valve spring lifters or compressors and constitutes an improvement on devices of the type disclosed in my prior Patent 2,064,264, granted December 15, 1936.

In such devices the relatively movable jaws are carried at the forward ends of rigid arms which are connected together in such a way as to cause relative expanding or contracting of said jaws responsive to relative longitudinal movement of said arms.

An object of the present invention is to so form the arms that portions thereof are disposed closely adjacent each other and in substantial longitudinal alignment, and to provide threaded actuating means connecting said portions in an improved manner to impart relative longitudinal movement thereto.

A further object is to provide an improved construction of threaded actuating means and also to provide improved connecting means between the threaded actuating means and the respective arms.

Other more general objects are to provide such a device which is adapted for economical mass production, while being of sturdy construction, efficient and reliable in operation.

In the accompanying drawings which illustrate the preferred embodiment of the invention:

Figure 1 represents a side elevation of a valve spring compressor embodying the invention, showing the jaws thereof in fully expanded position;

Figure 2, a plan view of the compressor in the position shown in Figure 1;

Figure 3, a side elevation similar to Figure 1, with the jaws in closed or contracted position;

Figure 4, a fragmentary detailed axial cross section of the hand wheel and associated parts, disclosing the interior construction and assembly of the hand wheel, actuating screw and bearing collar for same;

Figure 5, a cross section on the line 5—5 of Figure 4, looking in the direction of the arrows;

Figure 6, a front elevation of the nut which is employed with the actuating means of the invention;

Figure 7, a detail front elevation of the bearing collar;

Figure 8, a plan view of the nut shown in Figure 6; and,

Figure 9, an end elevation of said nut.

Referring now in detail to the accompanying drawings, the preferred embodiment of the invention therein illustrated comprises a pair of rigid longitudinally extending arms or beams

2

which are linked together for relative movement as aforesaid.

The lower of these which serves in the instant embodiment as a supporting arm or beam, comprises a pair of relatively transversely spaced sheet metal stampings or plates 1—1, the forward ends 3—3 of which together define a suitable work engaging jaw. Said ends 3—3 may be disposed for transverse adjustment towards or away from each other, as by means of the usual adjusting screw 5.

Rearwardly this arm 1—1 terminates in a pair of relatively transversely spaced oppositely perforated bearing portions 7—7 which preferably project upwardly to be in substantial longitudinal alignment with the upper or movable arm. It will be noted that these portions 7—7 are in close proximity to the rear end of the upper arms when the tool is in contracted position, as in Figure 3.

This upper arm also is preferably formed from a pair of relatively transversely spaced sheet metal stampings or plates 2—2, the forward ends of which are shaped and cooperate to define an upper jaw 4—4 which is opposed to the lower jaw 3—3 aforementioned for cooperation therewith. If desired the transversely opposed portions or furcations 4—4 of this upper jaw may be rendered relatively transversely adjustable by means of a usual adjusting screw 6.

These two arms or beams 1—1 and 2—2 are connected by rigid link members, the opposite ends of which are hingedly or pivotally connected thereto in such manner as to define a tetragon in which the various sides are pivotally connected so that longitudinal movement between the arms 1—1 and 2—2 will serve to vary the distance between the jaws 3—3 and 4—4.

The forward link 9 is preferably of channeled shape having its opposite ends received between the respective plates 1—1 and 2—2 of said arms and pivotally connected thereto in suitable manner, as by the transverse adjusting screw aforementioned, and the transverse pin or rivet 8 respectively passing through the ends of said link 9 and the opposed plates 1—1 and 2—2. The link 9 also serves as a spacer for the plates 2—2.

The rearmost link is preferably of composite construction embodying a pair of relatively transversely spaced link elements 10—10, each having its opposite ends pivotally secured to the respective plates 1 and 2 of its side of the device. A single rivet or in 11 may be passed through transversely opposed apertures in the plates 1—1 and the interposed lower ends of both link elements 10—10 to provide the pivotal

connection therefore, and a spacer sleeve 12 may be disposed on said pin 11 to maintain the link elements 10-10 and plates 1-1 in spaced relation. Each of said link elements 10 has its upper end pivotally secured to its respective plate 2 by a pivot portion 14' preferably integral with the threaded actuating nut 14.

The construction and arrangement of the arms and their connecting links in the preferred embodiment of the invention thus far described is substantially the same as is disclosed in my prior Patent 2,064,264, except insofar as same have been modified to adapt them for use with the improved actuating means of my invention.

Cooperating relatively rotatable threaded actuating means or elements are pivotally connected to the respective rear ends of the arms 1-1 and 2-2 to cause relative movement therebetween, with consequent expansion or contraction of the jaws 3-3 and 4-4 relative to each other.

One of these threaded elements comprises the nut 14, shown in detail in Figure 6, which is supported between the rear ends of the respective upper arm plates 2-2 for rotary movement about a transverse axis which is defined by integral pivots 13 extending from opposite sides of the nut 14 and received in bearing holes formed in the rear ends of arm members 2-2. In assembling the nut 14 and arm members 2-2 the outer ends of the pivots 13 are upset or riveted over as shown, after insertion through their respective bearing holes, to maintain the arm members or plates 2-2 against relative separation.

The pivot portions 14' for the link elements 10 respectively are disposed between the body of the nut 14 and the respective pivots 13, being of somewhat larger diameter than the pivots 13 to have their outer ends abut against the members 2-2 and maintain same in spaced relation.

A cooperating actuating element in the form of a screw 15 is threaded through the socket of nut 14, and is pivotally connected to the rear end of the supporting arm 1-1 by means of a thrust collar or bearing 16 for rotary movement about the axis of its threads, and swinging movement about an axis transverse thereto, while being positively held against axial displacement by said collar 16.

In the preferred embodiment illustrated I have provided an improved, economically produced and readily assembled construction for the screw 15 and its associated bearing or thrust collar 16. To this end the screw 15 includes an axial rear extension or shank comprising a relatively large diameter portion 20 adjacent the threaded portion, and a reduced diameter cylindrical portion 23 constituting the rear end portion of said shank. Formed in the shank portion 20 are flattened areas extending forwardly from the rear end thereof. These flattened areas 21 terminate forwardly in stop shoulders 24. A washer 25 formed with an opening therethrough which corresponds in shape to the cross section of the large diameter portion 20 is slipped onto the shank from the rear end thereof and moved axially into engagement with these stop shoulders 24. Thereafter the bearing or collar 16 is placed over the rear end of the shank and moved axially into engagement with the washer 25, the collar 16 being freely rotatably journaled on the cylindrical surface of portion 20.

A suitable hand wheel 26 having a mounting sleeve 27 integral therewith is then moved axially onto the shank of screw 15 and positioned thereon

in such manner that the forwardly presented end 28 of this sleeve 27 is presented towards the collar 16 to coat with the washer 25 in preventing relative axial movement between the collar 16 and screw 15.

The sleeve 27 is provided internally with connected axial bores 29 and 29' corresponding in shape and dimensions to the respective shank portions 20 and 23 to snugly receive same so that the engagement between the corresponding flattened areas 21 and 21' will prevent relative rotation between the screw 15 and hand wheel 26. It will be seen that engagement between the respective shoulders 22 and 22' at the junctures of the different diameter portions of the shank and sleeve bore respectively will limit the axial movement of the sleeve 27 towards the collar 16 and thus prevent binding of said collar between said sleeve and the washer 25.

The collar 16 is provided with diametrically projecting trunnions 17-17 which are respectively journaled in bearing holes formed in the portions 7-7 of the arm 1-1, to support the collar 16 and screw 15 therebetween, the ends of these trunnions 17-17 preferably being upset or riveted over to prevent separation between the end portions 7-7 of the arm 1-1.

With this arrangement the screw 15 is freely rotatable through the bearing or collar 16 and can swing about the axis of the pivots 17 as the arms 1-1 and 2-2 are disposed in different positions, and at the same time the screw 15 is held against axial displacement by the collar 16.

In the operation of the invention, which is believed to be apparent from the foregoing, the hand wheel 26 will be rotated to move the jaws of the device into relatively contracted position, as shown in Figure 3. In this position the jaws are inserted between the valve tappet and the valve spring retaining cup in a usual internal combustion engine, with the lower jaw 3-3 resting upon the tappet and the upper jaw 4-4 beneath the valve spring retaining cup. Thereafter, the hand wheel 26 is rotated to expand the jaws and thus raise and compress the valve spring to any desired degree. Even upon release of the hand wheel it will be apparent that the device will maintain the spring at any desired stage of compression.

The invention is also adaptable for use in the manner of a pair of pliers inasmuch as the hand wheel 26 and screw 15 may be rotated to cause relative contraction between the jaws 3-3 and 4-4.

It will be apparent that I have invented a screw actuated device which employs an actuating screw of minimum length and consequent minimum expense; and that the screw is assembled with the bearing or collar in an improved manner which facilitates rapid economical production, while resulting in a sturdy and extremely practical construction.

Having thus described my invention, I claim:

1. A valve spring compressor comprising rigid upper and lower longitudinally extending and relatively longitudinally movable arms respectively having relatively opposed jaws formed at their forward ends, a pair of relatively longitudinally spaced spreader links each extending between and pivotally connected to said respective arms to vary the distance therebetween responsive to longitudinal relative movement thereof, the rear end of said upper arm in its rearmost position terminating forwardly of the rear end of said lower arm, the rear end of said lower arm being formed with

transversely spaced bearing portions offset to lie in substantial longitudinal alignment with said upper arm, a nut mounted on said upper arm for pivotal movement about the axis of the pivotal connection between said arm and the rearmost of said links, the threaded bore of said nut extending therethrough perpendicularly to its pivotal axis, an annular bearing collar having diametrically projecting trunnions journaled in said respective bearing portions of the lower arm, an actuating screw rotatably journaled in and held against axial movement through said collar, said screw being in threaded engagement with said nut, and a hand wheel carried by said screw to facilitate manual rotation thereof.

2. A valve spring compressor comprising a pair of rigid longitudinally extending arms terminating at their forward ends in relatively opposed jaws, links extending between and hinged to said respective arms to vary the distance between said jaws responsive to relative longitudinal movement of said arms, the rear ends of said arms respectively terminating in transversely spaced portions, an annular bearing pivotally mounted between said portions of one arm, an actuating screw rotatable through said bearing, means associated with said actuating screw defining an annular groove therearound to receive said bearing and prevent relative axial movement between said screw and said bearing, and a nut pivotally carried by said portions of said other arm in threaded engagement with said screw.

3. In a device of the character described, an actuating screw adapted to be rotatably disposed through a bearing collar, said screw having indented flat surfaces extending in an axially parallel direction from one end thereof and terminating in stop shoulders, in combination with means associated with said screw to define a bearing seating groove comprising a washer having an

internal cross section similar to said screw disposed thereon in abutment with said stop shoulders, and a sleeve fixedly secured on said screw in axially spaced relation to said washer, the interior of said sleeve conformingly non-rotatably receiving said screw.

4. A valve spring compressor comprising a pair of relatively longitudinally movable rigid arms, a pair of relative longitudinally spaced rigid spreader links each extending between and pivotally connected to said respective arms to vary the distance between said arms responsive to relative longitudinal movement thereof, a nut pivotally connected to one of said arms for movement about an axis transverse to the common plane of said arms, a collar pivotally connected to the other of said arms for movement about an axis parallel to the pivotal axis of said nut, and an actuating screw rotatably journaled in and held against axial movement through said collar, said screw being in threaded engagement with said nut, whereby rotary movement of said screw will cause relative longitudinal movement of said arms.
